COMBINED RULER AND PENCIL HOLDER OR SIMILAR ARTICLE

Leonard Reichenthal, 970 E. 173rd St., New York, N.Y.

Filed Mar. 29, 1961, Ser. No. 64,532

Term of patent 14 years

(Cl. D52—6)

FIG. 1 is a top view of a combined ruler and pencil holder showing my new design;

FIGS. 2, 3 and 4 are side, left end and right end views, respectively on an enlarged scale, of said combined ruler and pencil holder;

FIG. 5 is an enlarged transverse sectional view taken substantially along the line 5—5 of FIG. 2; and

FIG. 6 is an enlarged longitudinal sectional view taken along line 6—6 of FIG. 1 and shown broken away for convenience of illustration.

I claim:

The ornamental design for a combined ruler and pencil holder or similar article, substantially as shown.
